UNITED STATES PATENT OFFICE.

CHARLES FREDERICK GREEN, OF ROMFORD, ENGLAND, ASSIGNOR TO A. B. DICK COMPANY, OF CHICAGO, ILLINOIS, A CORPORATION OF ILLINOIS.

INKING DEVICE FOR DUPLICATING MACHINES.

Application filed April 14, 1922. Serial No. 552,503.

To all whom it may concern:

Be it known that I, CHARLES FREDERICK GREEN, a subject of the King of Great Britain, residing at Roneo Works, Hornchurch Road, Romford, Essex, England, have invented certain new and useful Improvements in Inking Devices for Duplicating Machines, of which the following is a specification.

This invention relates to improvements in inking devices for use with rotary duplicating machines.

As a means for inking the cylinder of a duplicating machine, it has been proposed to provide an ink trough fitted with a roller

which is normally spring pressed directly against the cylinder to effect a transfer of ink thereto, but which may be moved manually against the action of the spring out of contact with the cylinder and latched in such position. Another construction heretofore devised has included a roller fitted in a pivotally mounted ink trough and adapted to automatically contact with and transfer ink to a superimposed roller for a certain number of revolutions of the printing cylinder and then to automatically swing into an inoperative position clear of said superimposed roller, the latter roller contacting the cylinder to transfer ink thereto.

These types of inking devices apply the ink over the complete surface of the printing cylinder, and when it is desired to apply ink to one particular point or points, where it is observed from the prints produced that insufficient ink has been applied, it has not been possible to ink that point without inking the whole surface. It is one of the aims of my invention to provide controllable means whereby ink may be distributed either to the entire cylinder or to only one or more particular points of the cylinder or not at all, as desired by the operator. A further object of my invention is to provide an inking device for rotary duplicating machines and one which is simple in construction and easy and efficient in operation. Other objects of my invention will be in part obvious and in part pointed out hereinafter.

In accordance with my invention, I provide a pivotally mounted ink trough or container fitted with a feed roller, and associate mechanism therewith whereby the operator may, by a simple manual operation, cause the ink trough to move either into one

position, in which the roller therein will contact with and transfer ink to a superimposed distributing roller for transfer to the cylinder, or into another position such that no ink will be transferred to the distributing roller. Thus the device may be manipulated to transfer ink to the entire cylinder for any number of revolutions, or to apply ink to one or more particular places on the cylinder which have not received a sufficient supply, or to cease transferring ink to the cylinder, as and when desired by the operator.

In order that a clearer understanding of my invention may be had, attention is hereby directed to the accompanying drawings wherein is illustrated one possible embodiment of my invention. Referring to the drawings, Fig. 1 is a sectional view of an inking device embodying my invention associated with a printing cylinder; Fig. 2 is a plan view of the inking device; and Fig. 3 is a sectional view of a detail of the means for operating the inking device.

Referring to the drawings, the printing cylinder 1 is rotatably mounted upon a fixed shaft 2 supported between suitable side standards, and receives its motion in the usual manner through spur or like gearing, and has secured thereon the usual wax stencil. Secured to the inner side walls of the printing cylinder are cams 3 which rotate with the cylinder and act at predetermined points upon rollers 4 secured to levers 5 supported at one end of arms 6 secured to the fixed central shaft 2. The said levers 5 carry at one end a felt roller 7, the other ends of said levers having studs 8 secured thereon supporting the ends of springs 9, the other ends of the springs being secured on a bar 10 fitted between the lower extremities of the arms 6. When the printing cylinder 1 is rotated in the direction of the arrow to effect the printing the rollers 4 drop down on to the inner cam surfaces 3^a as shown, so that the springs 9 act upon the ends of the levers 5, and impart a rocking action thereto, thereby swinging the felt roller 7 into contact with the printing cylinder. Situated beneath the felt roller 7 is the ink container 11, which is provided with hooks 12 for hooking over, or pivoting upon a bar 13 passing through the levers 5 supporting the felt roller 7, and secured to the arms 6. The ink container carries a roller 110

14 journaled in open brackets 15, and the ends of the inking roller are acted upon by springs 16, acting in the nature of scrapers to remove the ink from the edges of the inking roller 14 when the cylinder 1 is rotated in the direction of the arrow, but allowing a full supply of ink thereover when a reverse rotation is given to the cylinder.

The central fixed shaft 2 is bored out to 10 receive a spindle 17, one end of which passes out through the cylinder wall 1 as well as one of the side standards, and has a handle or lever 18 secured thereto, the other end having an external screw thread formed 15 thereon which engages with an internally threaded plate or arm 19 projecting through a slot 20 formed in the fixed central shaft 2, upon which the forward edge of the ink container 11 rests.

20 The ink container is provided with suitable ink filling means, such comprising a slide 21 having a knob 22 for moving the slide in the slideway 23.

The operation of the means for inking is 25 as follows:—

On movement being imparted to the printing cylinder 1 in the direction of the arrow, the operator presses the handle or lever 18, thereby turning the spindle 17 and causing 30 the plate or arm 19 secured thereon to raise the end of the ink container 11, so that the inking roller 14 contacts with the felt roller 7 which, as previously stated, has been lifted 35 into contact with the cylinder 1 through the action of the cams 3^a and springs 9. After two or three revolutions of the cylinder, the operator releases the pressure on the lever 18 whereby the spindle 17 turns, and with 40 it the plate or arm 19, and the ink container drops down to the position, shown in dotted 45 lines in Fig. 1, whereby the inking roller 14 is out of contact with the felt roller 7, but the latter always maintains contact with the printing cylinder at each revolution so as to distribute the ink thereto. Should it be 50 seen from the prints produced that there is a certain point where uniform printing has not been acquired, the operator can bring the ink to bear upon that point by depressing the lever 18 and reciprocating the cylinder backwards and forwards.

It has been found that the pressure exerted upon the printing cylinder by the felt roller 7 tends to spread the ink to the sides 55 of the printing surface and to counteract this tendency the scrapers 16 are placed at each end of the ink roller 14 so that the minimum quantity of ink is collected at the ends of the felt roller 7, which subsequently 60 absorbs the ink at its edges through contact with the printing cylinder, and by so doing counteracts uneven printing.

What I claim is:—

1. In a rotary duplicating machine, the 65 combination with a rotary printing cylinder,

of an ink container within the cylinder, fixed means pivotally supporting one end of said container at a place removed from the axis of said cylinder, and movable means including a member in engagement with said container at its other end, whereby said container may be pivoted on its fixed pivot toward and from the surface of said cylinder, substantially as described. 70

2. In a rotary duplicating machine, the 75 combination with a rotary printing cylinder, of an ink container within the cylinder, fixed means pivotally supporting one end of said container at a place removed from the axis of said cylinder, and means, 80 including a member manually movable from the outside of said cylinder, supporting said container at its other end, whereby said container may be pivoted on its fixed pivot toward and from the surface of said cylinder, substantially as described. 85

3. In a rotary duplicating machine, the 90 combination with a fixed shaft, a printing cylinder rotatably supported on said shaft, a fixed rod supported on said shaft, and an ink container pivotally supported at one end on said rod, of movable means including a member in engagement with the container at its other end, whereby said container may be pivoted on said shaft toward and from 95 the surface of the cylinder, substantially as described.

4. In a rotary duplicating machine, the 100 combination with a fixed shaft, a printing cylinder rotatably supported on said shaft, a fixed rod supported on said shaft, and an ink container pivotally supported at one end on said rod, of movable means, comprising a member movably supported on said shaft and engaging the other end of said container, for supporting the container at its other end, whereby said container may be pivoted on said shaft toward and from 105 the surface of the cylinder, substantially as described. 110

5. In a rotary duplicating machine, the 115 combination with a fixed shaft, a printing cylinder rotatably supported on said shaft, a fixed rod supported on said shaft, and an ink container pivotally supported at one end on said rod, of movable means, comprising a member movably supported on said shaft and engaging the other end of said container, for supporting the container at its other end, and means, manually movable from the outside of said cylinder, for moving said member, whereby said container may be pivoted on said shaft toward and from 120 the surface of the cylinder, substantially as described. 125

6. In a rotary duplicating machine, the 130 combination with a printing cylinder and a distributing roller therefor, of a fixed shaft, an ink container pivotally mounted upon a bar carried by an arm secured to said shaft,

- an inking roller carried by said ink container, and hand operated means for raising the ink container so that said inking roller contacts with and is rotated by said distributing roller, said means comprising a spindle movable in said shaft, a lever adapted to actuate said spindle and an arm movable with said spindle adapted to support the forward end of said container.
- 10 7. In a rotary duplicating machine, the combination with a printing cylinder and a distributing roller therefor, of a fixed shaft, a pivotally mounted ink container, an inking roller carried by said ink container, a spindle movable within said fixed shaft, said spindle extending exteriorly of said machine and having a handle thereon, the interior portion of said spindle having an arm projecting transversely through a slot in said fixed shaft, said arm supporting the forward end of said ink container, whereby movement of said handle in one direction moves said ink container to bring said inking roller into contact with said distributing roller to transfer ink thereto, and whereby movement of said handle in another direction is accompanied by movement of said inking roller into position out of contact with said distributing roller.
- 15 This specification signed this 30 day of 30 March, 1922.

CHARLES FREDERICK GREEN.
